UNITED STATES PATENT OFFICE.

SARE KING WONG, OF SAN FRANCISCO, CALIFORNIA.

DESIGN FOR A RADIOCABINET.

Application filed April 25, 1925. Serial No. 13,221. Term of patent 3½ years.

To all whom it may concern:

Be it known that I, SARE KING WONG, a citizen of China, residing at San Francisco, in the county of San Francisco and State of California, have invented a new, original, and ornamental Design for a Radiocabinet, of which the following is a specification, reference being had to the accompanying drawing, forming a part thereof.

Figure 1 is a front elevation of my design, and

Figure 2 is a side elevation of my design.

I claim:—

The ornamental design for a Radiocabinet, substantially as shown.

SARE KING WONG.
